UNITED STATES PATENT OFFICE.

CHARLES M. PRIOR AND CHARLES NELSON, OF NEW YORK, N. Y., ASSIGNORS TO
S. STERNAU & COMPANY, OF BROOKLYN, NEW YORK, A COPARTNERSHIP.

DESIGN FOR A KETTLE AND STAND.

41,722.

Specification for Design.

Patented Aug. 29, 1911.

Application filed June 2, 1911. Serial No. 630,907. Term of patent 7 years.

To all whom it may concern:

Be it known that we, CHARLES M. PRIOR, a citizen of the United States, and a resident of the borough of Manhattan, city, county, and State of New York, and CHARLES NELSON, a citizen of the United States, and a resident of the borough of Brooklyn, county of Kings, city and State of New York, have invented a new, original, and ornamental Design for a Kettle and Stand, of which the following is a specification, reference being had to the ac-

companying drawings, forming a part hereof, in which—

Figure 1 is a plan view; and Fig. 2 is a side elevation of the design.

We claim:

The ornamental design for kettle and stand, as shown.

CHARLES M. PRIOR.
CHARLES NELSON.
